UNITED STATES PATENT OFFICE

SIMON LEVISON, OF NEW YORK, N. Y.

EMBROIDERED LETTER FOR MONOGRAMS

Application filed May 16, 1932. Serial No. 611,578.

The present invention relates to improvements in individual embroidered letters used for forming monograms.

An object of this invention is to provide 5 an individual embroidered completely pre-formed monogram letter comprising upper and lower layers of ornamental needle-work and preferably with one or more filling layers and a layer of reinforcing fabric confined within the body of said letter.

Another object of this invention is to provide a composite monogram-letter made of a lower layer of needle-work, a superposed layer of reinforcing fabric tending to hold 15 the shape of the letter, one or more superposed filling layers of needle-work and a top layer of ornamental needle-work, the said reinforcing and filling layers being confined within the body of the letter.

Another object of this invention is to improve said individual monogram-letter with a border line of fine, closely spaced and tautly drawn stitching around the edge of the letter and forming a sharply defined non-raveling compressed outer edge of less height than the central portion of the letter and causing the cross-section of the finished letter to be a segment of a circle.

Another object of this invention is to use 30 chemically treated fabric for the said superposed reinforcing layer, the said letter being formed on the chemically treated fabric as a groundwork or base which decomposes and falls away all around the compressed 35 embroidered periphery on the application of heat to said embroidered letter and leaving the confined portion of the base fabric substantially intact and the individual embroidered letter as a clean sharply defined 40 and completely finished trimming article which will stand out in full relief from the surface of linings of garments to which it may be attached.

Another object of this invention is to use 45 reenforcing base fabric having an element of

resiliency, so that the finished letter containing the intact portion of said fabric will remain resilient and tend to retain its predetermined form.

With the above and other objects in view 50 the invention will be hereinafter more particularly described, and the combination and arrangement of parts will be shown in the accompanying drawing and pointed out in the claim which forms part of this specification. 55

Reference will now be had to the drawing, wherein like numerals of reference designate corresponding parts throughout the several views, in which:

Figure 1 is a plan view of the completely 60 finished letter S, formed according to the subject matter of this invention.

Figure 2 is an enlarged cross-section of 65 said letter, the section being taken as on line 2-2 in Figure 1.

Figure 3 is a sectional view of said letter, taken as on line 3-3 in Figure 2, and shows the superposed reinforcing base layer on top of the lower layer of needle-work.

In the illustrated embodiment of the in- 70 vention, the numeral 10, indicates an individual embroidered letter built up of a plurality of layers of textile materials, comprising a lower layer of needle-work 11, a superposed layer of reinforcing fabric 12, such 75 as buckram, one or more superposed filling layers of needle-work 13, forming the body of the letter, and a top layer of ornamental needle-work 14. As best shown in Figure 1, there has been provided a line of fine closely 80 spaced stitching 15, all around the edge of the letter, the said stitching being drawn taut and tending to compress the fabric edging of the letter into a sharply defined border and preventing it from unraveling. As best 85 shown in Figure 2, the outer edge portions on both sides of the cross-section are thus compressed and have a height less than the height of the filled and non-compressed central portion, and thus causing the cross-section of 90

the finished letter to be a segment of a circle. As best shown in Figure 1, the ornamental needle-work on the exposed outer surface 14, is preferably positioned crosswise of the body 5 of the letter. As shown in Figure 2, the layer of reenforcing fabric 12, has an element of resiliency and assists in forming the back face 16, of the letter 10, of flat form and also assists in maintaining the predetermined 10 form of the letter.

As shown in Figure 3, the reenforcing base fabric is originally of larger extent than an individual letter and a plurality of letters such as the letter S are embroidered on a 15 piece of such fabric. It is to be noted that in a preferred embodiment of the invention, the reenforcing base material is saturated with an acid solution before use as one of the elements in the finished letters and when 20 a plurality of letters are formed on a piece of said fabric, it is passed through a chamber heated to an elevated temperature of about 250° F. when the heat accelerates the action of the acid solution on the said fabric. The 25 compressed edging and the top and bottom layers of needle-work insulate and prevent the heat from acting upon the confined portion of the reenforcing base material with full intensity so that the said treated base 30 material is decomposed externally of the letter and remains substantially intact internally. The individual letters thus formed will lie flat and stand out conspicuously in full relief from the surface of linings of garments to which they may be attached for the 35 purpose of forming monograms.

It is to be noted that when the letters are formed with non-treated base material that the said material has to be trimmed away by 40 cutting all around the edge of the letter with a scissors.

It will thus be seen that there has been provided an individual machine embroidered completely pre-formed monogram letter 45 without any visible fabric background and which is resilient and stands out in full relief on the surface of the lining of a garment to which it is attached.

Having thus described my invention, I 50 claim as new and desire to secure by Letters Patent:

An individual composite machine embroidered letter for monograms, consisting of a lower layer of embroidery needle-work, 55 a superposed layer of reenforcing base fabric having an element of resiliency, one or more superposed layers of embroidery needle-work and a top layer of ornamental embroidery needle-work, the said letter being also provided with a line of closely spaced and tautly drawn stitching all around the edges for concealing and insulating said base fabric to prevent its disintegration, said edges being compressed and non-ravelling and of less 60 height than the central portion of the letter, 65

the cross-section of the finished letter being a segment of a circle and the letter being a completely pre-formed trimming article having shape-retaining resiliency without any visible base fabric background and adapted to project in full relief from the article which it is to identify. 70

Signed at New York, in the county of New York and State of New York, this 14 day of May, A. D. 1932. 75
